(57) **CLAIM**

The ornamental design for an electric bicycle frame, as shown and described.

DESCRIPTION

FIG. 1 is a top, front and left side perspective view of an electric bicycle frame showing our new design;

FIG. 2 is a top, rear and left side perspective view thereof;

FIG. 3 is a bottom, front and left side perspective view thereof;

FIG. 4 is a bottom, rear and left side perspective view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is a front top plan view thereof; and,

FIG. 10 is a bottom plan view thereof.

The broken lines in the drawings are included for the purpose of showing portions of the electric bicycle frame that form no part of the claimed design of the respective embodiment.

1 Claim, 8 Drawing Sheets
